DEVICE FOR REGAINING DIAMOND GRINDINGS (BOART) IN DIAMOND GRINDING
Louis de Beer, % N. V. Ahex, Erasmusweg 1077,
The Hague, Netherlands
Filed June 29, 1964, Ser. No. 379,050
10 Claims. (Cl. 51-270)

The invention relates to a device for regaining diamond grindings (boart) in diamond grinding, comprising a horizontal grinding disc and a device for catching boart, the latter comprising a fixed flat ring, the inner circular edge whereof fits substantially against the circumference of the said grinding disc and separates the air flowing outwardly from the upper and lower face of the said grinding disc from each other, and a boart catching filter collar concentrically to said separating ring above the upper surface thereof.

In known devices of this type a boart catching collar constitutes a torus shaped space, the underside of which is connected to a conduct from which the air is sucked, by means of a fan, through a filter mass, which is arranged in a separate container below the grinding table.

In such devices, wherein the air is sucked only locally from the catching collar, only a small portion of the valuable material can be caught, while moreover the apparatus is made complicated and expensive by the arrangement of the separate filter container with the fan and its driving means.

Especially a device is known wherein the said collar is so high as to produce hinder to the diamond grinder while laboring. To meet this disadvantage the known device shows two opposite interruptions in its collar for introducing the workpiece holders. Thus, however, a considerable portion of the material to be caught is lost, while yet the possibilities of arranging the holders for the stones to be ground and so also the number of stones which can be treated simultaneously remain restricted.

The principal object of the present invention is to obtain a device for regaining boart, which is simple and which does not produce any hinder in grinding, and which further will give a high yield in boart caught.

For this purpose, according to the invention, use is made of the phenomenon that a grinding disc which rotates at high speed (about 3000 r.p.m.) produces a stream of air along its circumference in outward direction.

Other objects of the invention will appear from the following description which is to be read in connection with the accompanying drawing which represents an embodiment of the device.

In the drawing:

FIG. 1 is an axial section through a diamond grinding device, as seen in the direction of the arrows I—I in FIG. 2;

FIG. 2 is a view of a grinding device;

FIG. 3 is a sectional view of a detail on an enlarged scale, as seen in the direction of the arrows III—III in FIG. 2.

In the drawing the axis of the grinding disc is indicated by 1, the grinding disc by 3 and the connection of the disc and the axis by 2 and 2'. The bearings and the driving mechanism of the grinding disc may be realized in the usual manner and are therefore not represented in the drawing. The grinding disc 3 is arranged in a circular opening 4' of a grinding table 4.

The grinding disc 3 is surrounded by a ring 5, the inner circular edge of which fits substantially against the circumference of the rotating disc.

By the high rotational speed of the grinding disc, which

2

is in practice in the order of 3000 r.p.m., the air layers immediately above and below the disc are thrown outwardly under the influence of the centrifugal force produced. In FIG. 1 such air streams at the edge of the disc are indicated by arrows. It will be clear that such air is supplied again from above and from below.

The air flow produced at the upper surface of the grinding disc will take along the diamond particles or boart on the disc surface; the boart supplied as grinding material as well as the grindings which are taken off the stones during the treatment.

The catching device comprises a filter unit 6 which is arranged above the separating ring 5 in the immediate vicinity of the circumference of the grinding disc 3. The ring shaped filter unit 6, the sectional view whereof is represented in FIG. 3, may consist of an upper and a lower bearer ring 7 and 8 respectively, and being connected to the inner edges of these rings a circular netting 9. Further it may be filled with any suitable filtering material 10 such as steel wool or several layers of netting. The outer circumference of the filter unit may also consist of netting material; anyhow it must allow the passage of air.

The filter unit 6 is covered at its upper side by a ring shaped element 11. The ring 11 and the filter unit 6 are connected detachably to the grinding table 3 in a manner to be described below.

The filter unit 6, the separating ring 5 and the cover ring 11 constitute a filter collar which is thus lying annularly around the edge of the grinding disc. The air which is streaming outwardly, under the influence of the centrifugal force, with high speed along the whole upper surface of the disc, conducts the diamond particles immediately to the filter ring 12, to which a great effective surface and a relatively small air resistance can be given, which enables to obtain effective regaining of the valuable material without arranging any special sucking device. It has appeared that this result can be obtained with a filter unit which projects only over a small distance over the upper surface of the grinding disc and of the grinding table. In this way a grinding disc 3 remains readily accessible along its whole circumference for the grinding labor, while a complete view on the work is attained. The cover ring 11 serves as a protection for the grinder.

It will further be noted that the centrifugal force on the air is the only driving medium for the entire boart catching.

The fixed circular plate 5 which fits against the circumference of the grinding disc 3 prevents the air which is displaced outwardly along the undersurface of the disc to flow upwardly along the outer edge, this would disturb the effect which is obtained, because this would make the upper air stream bend so that it would not completely reach the filter unit 12 anymore.

In the embodiment shown, special measures have been taken to provide disappearance of the air behind the filter unit 6 in such a way that the resistance to the air flow is reduced as far as possible. FIG. 1 shows a grinding table 4, the top of which is somewhat lower than the upper surface of the grinding disc 3. The grinding table supports a plate 18 with a central circular opening 18' around the grinding disc member 2', and a plate 19, to which the separating ring 5 is connected, both plates being spaced by means of a plurality of guiding members 22, thus leaving a passage for the air thrown outwardly by the grinding disc portion lying below the separating ring 5.

Spaced in relation to plate 13 is a third plate 20 with a circular opening 21, which surrounds the filter unit

6 in the vicinity of the upper outer edge thereof. The plate 20 constitutes the upper surface of the grinding table 4, and the space below offers a free passage for the air which has passed the filter unit 6.

Spacing of the plates 19 and 20 may also be obtained by a plurality of guiding members 23, which, just as the grinding members 22, may have a direction corresponding with the direction of the air stream when leaving the disc 3.

In order that the boart caught may easily be taken away from the filter 6, after several days of working, the filter 6 is executed as a detachable unit, which rests upon the separating ring 5 and is covered by the ring 11. The ring 11 may be placed upon the filter unit by means of a hook 12, which corresponds with an opening 13 in the upper ring 7 of the filter unit. After a small relative rotational displacement vertical taking away of the cover ring 11 is prevented, while its rotation and simultaneously taking away of the filter unit 6 is prevented by means of a locking mechanism 14. This locking mechanism may be a so called cylinder lock, arranged in the cover ring 11, and comprising, as is schematically represented in the drawing, a pin member 15, projecting through a hole in the filter unit, and cooperating with a block member 16 on the separating ring 5.

In FIG. 1 at the right side, the lock 14' shows the key 17 with the unlocked position, while the left lock 14 shows the locked position.

What I claim is:

1. Device for regaining diamond grindings (boart) in diamond grinding on a grinding mill, comprising a horizontal rotatory grinding disc and a device for catching boart, the latter comprising a fixed flat ring, the inner circular edge thereof fitting substantially against the circumference of the said grinding disc and separates the air flowing outwardly from the upper and lower face of the said grinding disc from each other and a boart catching filter collar concentrically to said separating ring and above the upper surface thereof, wherein the air, flowing outwardly from the upper surface of the said disc, together with the diamond particles suspended therein enters rectilinearly, air outlet openings being provided at the outer side of the said filter collar.

2. Device as claimed in claim 1, wherein a flat ring covers the upper side of the filter collar concentrically with the latter along the whole circumference of the said grinding disc and adjoining the upper surface thereof, while its inner edge projects slightly further inwardly than the filter collar, a gutter shaped filtering space being formed bordered by the said filter collar, the said separating ring, the outer side of the said grinding disc and the said covering ring.

3. Device as claimed in claim 1, wherein the entire said boart catching device is arranged exclusively in the region which surrounds the circumference of the grinding disc.

4. Device as claimed in claim 1, wherein the said air outlet openings open into the surrounding air, the difference of pressure on the inner and outer side of the said filter being exclusively obtained from the centrifugal force on the air produced by the rotation of the grinding disc mechanism.

5. Device for regaining diamond grindings (boart) in diamond grinding on a grinding mill, comprising a horizontal rotatory grinding disc and a device for catching

boart, the latter comprising a fixed flat ring, the inner circular edge thereof fitting substantially against the circumference of the said grinding disc and separates the air flowing outwardly from the upper and lower face of the said grinding disc from each other and a boart catching filter collar concentrically to said separating ring and above the upper surface thereof, the said filter collar being attached to said separating ring so as to form a removable unit with a concentric cover ring, said cover ring being situated immediately above the inner edge of a circular opening in a grinding table in the centre of which the grinding disc is arranged.

6. Device as claimed in claim 5, wherein the said filter unit comprises at least one ring shaped filter between 15 and attached to an upper and a lower bearing ring, a circular netting extending between the said bearer rings, the upper most portion of which is connected to the said cover ring.

7. Device as claimed in claim 5, wherein at least one lock member is provided as a means for removably connecting the said filter unit and the said cover ring to the grinding table.

8. Device for regaining diamond grindings (boart) in diamond grinding on a grinding mill, comprising a horizontal rotatory grinding disc and a device for catching boart, the latter comprising a fixed flat ring, the inner circular edge thereof fitting substantially against the circumference of the said grinding disc and separates the air flowing outwardly from the upper and lower face of the said grinding disc from each other and a boart catching filter collar concentrically to said separating ring and above the upper surface thereof and wherein a grinding table contains at least one passageway for air, which 35 passageway is connected to the space at the outer circumference of said filter above said separating ring, and further at least one passageway for air, which is connected to the space below said separating ring.

9. Device as claimed in claim 8, wherein the upper portion of the said grinding table comprises one plate-like member which is provided with a central circular opening registering with said separating ring and spaced with respect to the lower portion of the said grinding table so as to form a passage for the air which is flowing outwardly by rotation of the grinding disc portion situated below said separating ring, and an upper similar plate-like member with a central circular opening which registers with the outer circumference of the filter in the vicinity of the upper edge thereof, and being spaced with respect to the first mentioned plate-like member 50 to form a passage for the air which has passed the filter in outward direction under influence of the rotation of the grinding disc portion situated above said separating ring.

10. Device as claimed in claim 9, wherein both the passageways for the air above and below the separating ring contain a plurality of guiding members for the air stream in a direction corresponding with the direction of the air stream when leaving the grinding disc.
